UNITED STATES PATENT OFFICE.

ELISHA WATERS AND GEORGE A. WATERS, OF TROY, NEW YORK.

LIFE-PRESERVER.

SPECIFICATION forming part of Letters Patent No. 315,095, dated April 7, 1885.

Application filed August 4, 1883. (No model.)

To all whom it may concern:

Be it known that we, ELISHA WATERS and GEORGE A. WATERS, of Troy, in the county of Rensselaer and State of New York, have invented certain Improvements in Life-Preservers, of which the following is a specification.

This invention relates to that class of life-preservers which are designed to be worn on the person, the aim of the invention being to produce an article which may be manufactured cheaply, which shall be light in weight, which will automatically adjust itself to persons differing in size, and which will be free from liability of disarrangement when in use.

To this end the invention consists, essentially, in the combination of two floats designed to be used one at the chest and the other at the back, connected by adjustable or flexible bearings designed to pass beneath the arms of the user.

It also consists in combining with said floats connections which are adjustable or variable in length.

It also consists in the connected floats of cylindrical form adapted to be rolled readily into position upon the person of the wearer.

It also consists in the floats constructed of paper, waterproofed, and in the means for protecting the same against abrasion, and in minor features, which will be hereinafter more fully explained.

Life-preservers for individual use have heretofore been constructed in a great variety of forms, and ordinarily of but two classes, the one consisting of flexible chambers or floats to be inflated for use, and the other consisting of cork or similar buoyant material contained in an envelope of canvas or its equivalent. Preservers of the first class, owing to their rapid decay and deterioration, and to the liability of the closing-valves to fail when in action, are going rapidly into disuse. Preservers of the second class are objectionable because of their excessive weight, of their cumbrous form, and of the difficulty of adjusting them properly and securely in position upon wearers of different sizes during the hurry and excitement which occurs on occasions which render their use necessary. It is to avoid these difficulties that the present invention is designed.

Referring to the accompanying drawings, Figure 1 represents a perspective view of the improved preserver in its most simple and preferred form. Fig. 2 is a top plan view of the preserver in a modified form, portions of the same being shown in section to illustrate the details of construction. Fig. 3 represents an end view of the same.

Referring to Fig. 1, A A represent two hollow cylindrical floats, preferably of equal size and length, a length of about eleven inches and a diameter of from four to five inches being found to answer an excellent purpose. These floats, which may be constructed of any suitable material, but which are preferably constructed of paper, as hereinafter more fully explained, are arranged parallel with each other and united at their ends by transverse connections B, which may be of any suitable form and material, of a length sufficient to pass beneath the arms of the wearer, one float being located at the chest and the other behind the back. These connections are designed to rest beneath the arms and sustain the weight of the user and to retain the floats in proper position at the front and rear.

When adjusted for use upon a person of definite size, the connections may be rigid; but it is preferred to render them elastic or extensible, in order that they may readily adjust themselves to persons of different sizes.

It is to be noted as a peculiarity of our preserver that the two floats are made of an elongated form, and that the connections are extended between their extreme ends. This arrangement causes the weight to be carried directly at the ends of the plates, and insures their proper retention in the proper position with respect to the person of the wearer, avoiding those dangers and difficulties which are commonly encountered in the use of floats which are free to change their position.

In Fig. 1 the connections are represented of webbing or equivalent woven material of a flexible nature. When thus constructed, it is not essential that they shall be adjusted in length to suit the person of the wearer, inasmuch as their flexibility will admit of their sinking at the middle beneath the weight of the wearer, and thus drawing the two floats snugly into position against the breast and back. The

essence of the invention in this regard consists in connecting two floats, one designed for use at the breast and the other at the back, by connections to pass beneath the arms of the user, and it is manifest that the sectional form of the floats may be modified as desired. It is preferred, however, to adopt the cylindrical form for various reasons, the principal one being that when the connections are pivoted, 10 as shown, at the center of the floats, the floats may revolve freely, and thus be conveniently rolled into position upon the body, either over the head or over the feet, and in like manner removed conveniently.

15 In Fig. 1 the connecting-straps of webbing are represented as being provided with buckles to admit of their length being increased or diminished, and as being passed through slots in the ends of plates D, which are secured to 20 the ends of the floats by pivots or journals E.

Passing next to the construction represented in Figs. 2 and 3, it will be seen that the floats are similar to those represented in Fig. 1, but that the flexible connecting-straps are 25 replaced by extensible spring-connections. At each end of the device a tube, F, designed to rest beneath the arms of the user, contains a strong spiral spring, G, the ends of which are extended beyond the tube and connected to 30 caps H, which are in turn pivoted to plates or links D, pivoted centrally to the end of the floats. The springs thus applied serve as a connection between the two floats, and tend to draw them toward each other snugly 35 against the person of the user, at the same time permitting them to be separated a sufficient distance to admit of the preserver being applied to persons large in body. As a matter of protection, to prevent the spring 40 from being subjected to excessive strains and to prevent the floats from separating in the event of the fracture of the spring, a strong cord or chain, K, is passed centrally through each spring and secured at its ends to the respective caps H, this string being of suitable 45 length to permit the elongation of the spring to the proper degree. The springs may be secured to the caps in any suitable manner; but it is preferred, as shown in Fig. 2, to recess 50 the caps, insert the spring therein, and insert a central plug, M, which engages within the end of the spring, and which is provided with a threaded neck extending through the rear end of the cap and secured by an external nut, 55 O, thereon. The employment of the links or plates D is preferred, for the reason that it permits the floats to adjust themselves more freely to the person of the wearer; but, if desired, the caps H may be pivoted directly to 60 the ends of the floats, or the ends of the spring otherwise attached to the floats. The tubes or sleeves F serve to prevent the chafing or cutting action of the springs; but they may be omitted or replaced by a flexible covering of 65 any suitable character.

It will be observed that the spring and its

attachment constitutes in effect the flexible connection between the two floats.

Passing now to the construction of the floats, it is preferred to form them of sheets of paper 70 wound tightly one upon another and united by glue, a solution of rubber, or other appropriate adhesive material, the ends being composed either of laminated paper in like manner, or of wood or other suitable material inserted into the body. 75

After being constructed, the paper cylinder is to be treated by waterproofing varnishes, paints, or other coating, to prevent the destructive action of the water thereon. To give 80 them additional strength and to protect them from abrasion, their outer surfaces are usually covered with canvas or other suitable fibrous material, P, glued or cemented tightly thereon, and finished by a coating of paint, varnish, or 85 other material adapted to resist the action of the water.

As a further means of strengthening the floats and protecting them from injury, we prefer to encircle the end of each by a metallic 90 band, R, of angular form and cross-section, adapted to bear upon the periphery, and also against the outer or end face of the cylinder, as shown.

The employment of paper is considered 95 preferable to that of any other known material on account of the cheapness, lightness, and rigidity of the resulting cylinder.

We are aware that cylindrical floats are old, and that floats have been united in two groups 100 by means of conducting-straps constituting a harness to be passed over the shoulders and about the body, the harness requiring to be adjusted and fastened each time that the device is applied to the body of the user, and 105 to such construction we lay no claim.

It will be noted as a peculiarity of our construction that there are but two floats, and that these floats are of a rigid character, and adapted to extend one across the back and the 110 other across the breast, and that they are united at both extremities by flexible connections designed to remain permanently in place. This construction permits the device to be adjusted instantly in place upon the person, and avoids 115 the difficulty and danger incident to the application of the usual harness.

The application of the connections to the two ends of the plates in position to pass beneath the arms of the wearer is highly advantageous, in that it insures the retention of the floats in position, preventing their accidental displacement, and allowing the wearer the free use of his arms for the purposes of propulsion. 120

The present invention is restricted to those 125 matters and things which are hereinafter claimed, and as to all matters which may be described or shown but which are not claimed the right is reserved to make the same the subject of a separate application.

We are aware that a strap provided with a buckle and designed for application about the 130

body has been provided also with two small | floats adapted, as described, to extend across the back and chest, respectively, and spring-
5 substantially rectangular floats arranged to connections, substantially as described, unit-
slide freely thereon; but by employing elon- ing said floats at both ends, whereby the float-
gated floats and connecting them at both ex- 40
tremities with flexible devices we provide a
10 preserver which may be instantly applied,
which cannot be displaced, and which may
be given sufficient buoyancy to maintain the
15 head of the user well above the surface of the
water without interfering in the slightest with
the use of his arms.

Having thus described our invention, what
we claim is—

1. The improved life-preserved consisting
15 of two rigid elongated floats adapted to extend
across the back and chest, respectively, com-
bined with flexible devices connecting said
floats permanently at both extremities, and
adapted, as described, to pass beneath the arms
20 of the wearer, whereby the preserver is adapt-
ed for instantaneous application without spe-
cial adjustment or connection of its parts, and
the floats retained in proper position when in
use.
- 25 2. In a life-preserved, two rigid elongated
cylindrical floats, *a a*, and two extensible con-
nections, *b b*, uniting said floats permanently
at their two ends, as described and shown.
- 30 3. In a life-preserved, the combination of two
cylindrical floats and two connections uniting
the ends of said floats and pivoted or swiveled
thereto, whereby the floats are permitted to
revolve in being placed in position upon the
35 person.
4. In a life-preserved, two elongated rigid

floats adapted, as described, to extend across
the back and chest, respectively, and spring-
45 connections, substantially as described, unit-
ing said floats at both ends, whereby the float
is adapted for application to persons differing
in size without special adjustment, and the
floats retained in proper position.

5. In a life-preserved, the combination of the
two floats, the plates pivoted to the ends of
said floats, and the intermediate springs con-
necting said floats.

6. In combination with the floats and the
connecting-springs, the sleeve or covering *F*,
applied to said spring.

7. In a life-preserved, the combination of 50
the rigid floats, the connecting-springs, and
the connecting-cords adapted, as described, to
limit the extension of the springs and to re-
ceive the weight of the user in the event of the
breakage of the springs.

8. In combination with the two floats, sub-
stantially as described, the plates *D*, pivoted
thereto, the springs, the caps applied to said
springs, and a pivotal connection between said
caps and the plates.

9. In a life-preserved, the combination of
the paper body, the fibrous covering applied
thereto, and the rings *R*, applied, as described,
to the ends of said body.
